Patented July 9, 1918.

INVENTOR

LESTER L. KELL

by Dr. George Doug Amy.

UNITED STATES PATENT OFFICE.

LESTER L. KELL, OF ST. LOUIS, MISSOURI.

SWING.

1,272,273.

Specification of Letters Patent.

Patented July 9, 1918.

Application filed May 23, 1916. Serial No. 99,310.

To all whom it may concern:

Be it known that I, LESTER L. KELL, a citizen of the United States, and resident of St. Louis, Missouri, have invented certain new and useful Improvements in Swings, of which the following is a specification containing a full, clear, and exact description, reference being had to the accompanying drawings, forming a part hereof.

- 10 My invention relates to improvements in swings and the object of my invention is to provide a swing comprising a wheeled vehicle such as a baby carriage, and a suspending means therefor which is easily set up for use and applied to the baby carriage, and is inexpensive in construction, neat in appearance and separable from the baby carriage so that the baby carriage may be employed otherwise than as a swing.
- 15 The cord adjuster, shown and described, has been made the subject-matter of a separate application which was filed March 18, 1918 and serially numbered 223,059.

With the above purposes in view my invention consists in certain novel details of the construction and arrangement of parts which will be hereinafter fully, clearly and concisely set forth in my specification, pointed out in my claims and illustrated by the accompanying drawings, in which

Figure 1 is a perspective view of a swing embodying my invention;

Fig. 2 is an elevation partly in section showing the hook in connection with the baby carriage;

Fig. 3 is an elevation of a cord adjuster employed in my swing;

Fig. 4 is a sectional elevation of the cord adjuster and;

40 Fig. 5 is an elevation of the cord adjuster taken diametrically opposite Fig. 3.

Referring by numerals to the accompanying drawing, 6 designates the baby carriage, 7 the wheels thereof and 8 the handle, all of 45 which in their specific construction form no part of my invention except in combination with the suspending means for the baby carriage.

While I have shown the one type of baby carriage I wish it to be understood that my device is adaptable to all forms of baby carriages. The suspending means *per se* comprises a pair of screw-hooks 9 arranged to be secured in any convenient overhead 55 support which is not shown.

A pair of rings 10 may be readily sus-

pended from or removed from said hooks 9 and form with said hooks a bearing offering a minimum of resistance to a free swinging motion. Secured to said rings are the cords 60 11 arranged in pairs there being a pair connected with each ring and by preference the pairs are formed from a single strand secured at its middle to the ring. Over each of the cords 11 there is an adjuster 12 the 65 cord being extended through an opening 13 extending to the approximate center of the adjuster, thence laterally through an opening 14, thence around the outside of the adjuster and located in a groove 15, extending 70 or belting the entire circumference of the adjuster, thence into the opening 14 and thence through an opening 16 paralleling the opening 13 and thence looped or doubled backwardly upon itself and its end extended 75 upwardly through the opening 16, thence laterally through an opening 17 paralleling the opening 14 where its end is knotted and seated against a shoulder 18 formed in the opening 17.

In the bight of the loop 19 of each cord, I secure a ring 20 from which ring and preferably integrally formed therewith, there extends a hanger comprising a straight portion 21, a bowed portion 22 and at the bottom of said bowed portion a V-shaped hook portion 23. In use two of these V-shaped hook portions are hooked over the front wheels between the spokes thereof and engaging the rims of the baby carriage, and 90 the other two hooks are placed over either the rearmost wheels or the handle 8.

I make reference to these two points of application to the baby carriage for the reason that in some baby carriages there is a 95 preponderance of weight to the rear of the rearmost wheels and in such carriages I suspend from the handle in order to prevent upsetting by over balancing rearwardly. When there is an even balance of weight in 100 the baby carriage, that is an approximately even distribution of weight over the front and rear wheels of the carriage, I place a hook at each wheel. It will be obvious that there is little or no danger of the hooks becoming detached from either the rims of the wheels or handle because of their V-shape which exerts a wedging connection thus tending to firmly hold the suspending means connected with the carriage and by 110 reason of the bows connecting with the hooks there may be a considerable vibration in the

carriage due to the motions of a child therein in which motions will be taken up by the said bowed portions instead of movements of the hooks with relation to the carriage parts, as would result were it not for the bows.

By reason of the cord adjusters the device is readily adaptable to various heights of ceilings or other points of suspension and by 10 reason of the peculiar construction of the adjusters, that is by reason of the arrangement of the openings and groove there is a maximum friction or surface engagement between the cord and adjuster.

15 The attachment of the hooks to the wheels offers a swinging motion upon the bearings between the wheels and their axles requiring a minimum of exertion to affect and which motion will by reason of said bearings continue a relatively long time without effort.

By reference to Fig. 2 of the drawing, it will be observed that the bows 22 of the suspending devices permit the attachment to baby carriages having mud guards about 20 the wheels.

Having thus described my invention, what I claim as new therein and desire to secure

by Letters-Patent of the United States therefor is:

1. A suspension means for swings comprising a cord, and an element comprising an eye, for connection with the cord, a wedge-shape hook, for connection with the swing body, and a curvilinear body between the eye and hook, substantially as shown and for the purposes stated.

2. The combination with a body, having supporting wheels, of a suspension means therefor, comprising an overhead bearing consisting of readily separable elements, cords for connection with certain of the separable elements, means for connecting said cords with the wheels of said body comprising a bowed body portion and a wedge-shape hook, and means for adjusting the 45 cords, as to lengths.

In testimony whereof, I have signed my name to this specification, in presence of two subscribing witnesses.

LESTER L. KELL.

Witnesses:

MELLY R. CHANDLER,
W. S. CROUSE.
